UNITED STATES PATENT OFFICE.

WALTER E. OLSON, OF CHICAGO, ILLINOIS.

METHOD OF PREPARING STRANDS FOR WEAVING RUGS AND THE LIKE.

Application filed September 24, 1921. Serial No. 502,897.

To all whom it may concern:

Be it known that I, WALTER E. OLSON, a citizen of the United States, and a resident of the city of Chicago, county of Cook, and State of Illinois, have invented certain new and useful Improvements in Methods of Preparing Strands for Weaving Rugs and the like, of which the following is a specification.

My invention relates to improvements in methods of preparing strands for weaving rugs and the like, and has for its object the provision of an improved method for the purpose by means of which strong, durable and attractive rugs, carpets and the like may be rewoven from old material such as old carpets, rugs, blankets, clothing and the like.

Other objects will appear hereinafter.

The invention consists in the methods of procedure hereinafter described and claimed.

The invention will be best understood by reference to the accompanying drawings forming a part of this specification and in which,

Fig. 1 is a partial top plan view of a cutting table employed in the process.

Fig. 2, an enlarged plan view of a portion of one of the strips of material cut by said cutting table,

Fig. 3, an enlarged, exaggerated diagrammatic view illustrating substantially the appearance of an enlarged section taken on line 3—3 of Fig. 2,

Fig. 4, a perspective view illustrating one of said strips in the process of twisting the same,

Fig. 5, a detail view illustrating the twisting spindle employed in such twisting,

Fig. 6, a partial view of a strip partially twisted,

Fig. 7^a, an enlarged detail view similar to Fig. 3 but diagrammatically illustrating the position of the threads assumed at an early stage in the twisting, and

Fig. 7^b, a view similar to Fig. 7^a but illustrating the final position of the threads assumed from the twisting.

The preferred method of procedure consists in ripping carpets, rugs and the like into the original carpet widths from which they were originally formed. These widths are then dampened to render them flexible and capable of easy manipulation. They are then passed through an ordinary cutting machine and cut into strips. The cutting operation is substantially illustrated in

Fig. 1 of the drawings wherein 8 represents one of such carpet strips being cut into smaller strips. The cutting machine is an old and well-known machine for the purpose and comprises a suitable cutting table 9 provided with a vertically reciprocating knife 10 co-operating with the cutting blade or head 11 arranged at the edge of the table 9 and equipped with a suitable feed roller 12 as indicated, the machine operating in the usual way to cut the strips 8 into the smaller transverse strips 13 as indicated.

The transverse or warp threads of the strip 12 are usually more or less distorted from the original straight lines assumed in the original weaving process, especially where used and worn carpets and rugs are being employed as is usual in this class of weaving. The dampening of the strips 8 tends to soften the same, loosening the glue or stiffening material usually contained and permitting of straightening of the strip 8 by the operator as the same is automatically fed through the cutting machine. The machine is adjusted to cut the strip 8 into transverse strips 13 containing four of the original warp threads or strands thereof. As far as possible the operator aims to cut the strip 8 along lines parallel with these warp threads so as to prevent cutting or breaking the edge threads. The strip thus produced is illustrated diagrammatically in Figs. 2 and 3 and, it will be observed, contains two sets of interior central warp threads 14 and sets 15 and 16 adjacent the cut edges thereof.

Then the strip 13 has one end inserted in a clamp 17 at the end of a rotating spindle 18 and whereby said strip is twisted as indicated in Fig. 4. The first effect of this twisting will be to withdraw the warp threads 15 and 16 from the body of the material and arranging said threads on the outside of the strip as indicated in Fig. 7^a, thus freeing the edge fibers of the strip 13 to form a nap. As the twisting proceeds the threads or strands 15 and 16 are drawn to the centers of the opposite sides of the strip 13 as indicated in Fig. 7^b, and whereby the threads 15 and 16 are associated with the threads 14 to form a strong central core for the strip 13 thus reinforcing and strengthening the same and preventing any loss of original strength thereof in the weaving process. The strips or strands thus formed and twisted are then permitted to dry and are woven

into rugs, carpets and the like by being used as the woof threads or strands in an ordinary weaving machine. The re-woven rugs and carpets thus formed will be found to be 5 strong, durable and reversible in use, the fibers projecting from the edges of the strips 13 forming a double nap on both sides thereof.

While I have illustrated and described 10 the preferred method of procedure and apparatus for carrying on the same, these are capable of variation and modification without departing from the spirit of the invention. I, therefore, do not wish to be 15 limited to the precise method and apparatus set forth but desire to avail myself of such variations and modifications as come within the scope of the appended claims.

Having described my invention, what I 20 claim as new and desire to secure by Letters Patent, is:

1. The method of preparing strands for weaving rugs and the like which consists in first dampening a strip of woven material; 25 straightening and cutting said strip into smaller strips; and then twisting said smaller strips to form strands for weaving, substantially as described.

2. The method of preparing strands for 30 weaving rugs and the like which consists in first dampening a strip of woven material; straightening and transversely cutting said strip into smaller strips upon lines substantially parallel with the transversely extending woven strands thereof; then twisting said smaller strips to form strands for weaving; and then drying said strips, substantially as described.

3. The method of preparing strands for 40 weaving rugs and the like which consists in first dampening a strip of woven material;

straightening and cutting said strip into smaller strips containing a plurality of longitudinal strands; and then twisting said smaller strips until the longitudinal threads 45 at the edges thereof are drawn out of the material and arranged against the sides thereof to form strands for weaving, substantially as described.

4. The method of preparing strands for 50 weaving rugs and the like which consists in first dampening a strip of woven material; straightening and transversely cutting said strip into smaller strips along lines substantially parallel with the transverse woven 55 strands thereof and containing a plurality of such strands; then twisting said smaller strips until the longitudinal strands at the edges thereof are drawn out of the material and arranged against the sides thereof; and then drying said twisted strips, substantially as described.

5. The method of preparing strands for weaving rugs and the like which consists in first dampening strips of carpet material; 65 straightening and transversely cutting said strip into smaller strips containing at least four of the transverse woven strands thereof; then twisting said smaller strips until the edge strands thereof are drawn out of 70 the material and arranged substantially centrally against the sides thereof; and then drying said twisted strips to form strands for weaving, substantially as described.

In testimony whereof I have signed my 75 name to this specification in the presence of two subscribing witnesses.

WALTER E. OLSON.
